UNITED STATES PATENT OFFICE

EDWIN W. GOESER, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA.

ONE-PIECE ROTARY

Application filed November 9, 1926; Serial No. 147,235. Renewed December 14, 1929.

My invention relates to the drilling of oil wells by the so-called rotary system and relates particularly to a rotary machine.

In the art it is practice to drill a well by use of a bit attached to the lower end of a drill pipe. This drill pipe extends upward through the hole already drilled and through the floor of the derrick. Mounted on the floor of the derrick is a rotary machine which drives the drill pipe. The rotary machine commonly used has a base and a rotary table supported thereby, this rotary table being driven by means of a pinion attached to a pinion shaft. The ordinary rotary machine base is made in two halves which are secured together by bolts. The base is supported on a pair of wooden skids which are secured to it by bolts. It is well known that the rotary table is subjected to severe strains in deep well drilling which causes the two halves of the base to work loose, this resulting in a distortion of the parts and in a breakage of some part.

It is an object of this invention to provide a rotary machine having a special design of base which will be more rigid and will be stronger than the bases of the ordinary rotary machines so that the rotary machine of my invention will be able to endure the strains to which such machines are ordinarily subjected when a deep well is drilled.

Other objects and advantages of the invention will be made evident hereinafter.

Referring to the drawings in which I illustrate a preferred form of my invention,

Fig. 1 is a diagrammatic view illustrating the utility of the invention.

Fig. 2 is an elevational view, partially sectioned, of the invention.

Fig. 3 is a plan view of the base of the invention.

Fig. 4 is a section taken on the line 4—4 of Fig. 3.

Fig. 5 is a section taken on the line 5—5 of Fig. 3.

Referring to Fig. 1, I show a derrick 11 having a rotary machine 12 embodying the features of my invention mounted on a floor 13 thereof. Extended through the rotary machine 12 is a drill pipe 14 which is rotated

thereby. The lower end of the drill pipe 14 extends into a partly drilled well 16 and has a bit 17 attached to the lower end thereof. The upper end of the drill pipe 14 is partially supported by a traveling block 19.

Referring to Figs. 2 to 5 inclusive, the rotary machine 12 has a base 21 including the important features of the invention. As illustrated best in Figs. 2, 3 and 4 the base 21 has a horizontal plate 22. The horizontal plate 22 has a large opening 23 which is surrounded by a vertical cylindrical wall 24. A horizontal wall 25 provides an annular ledge 26 on which a bearing race 27 (Fig. 2) is supported. The bearing race 27 supports conical roller bearings 28, which roller bearings in turn support an upper bearing race 29. The upper bearing race 29 is pressed into an annular channel 31 of a rotary table 32, the rotary table 32 being rotatably supported.

The rotary table 32 has a central cylindrical projection 34 which extends downward inside the cylindrical wall 24. The projection 34 surrounds an opening 35 formed through the rotary table. The rotary table 32 is held in the position shown in Fig. 2 by means of a hold-down ring 37. The hold-down ring 37 is provided with flanges 38 which are secured by bolts 39 to the base 21. The bolts 39 extend through openings provided in flat faces 40 of the base, over which faces the flanges 38 extend.

Formed on the rotary table 32 is a bevel gear 42 which is engaged by a pinion 43, by means of which the rotary table 32 is revolved. The plate 22 of the base 21 is provided with an opening 45 through which the lower portion of the pinion 43 extends. The pinion 43 is attached to the inner end of the pinion shaft 46, which pinion shaft 46 is rotatably supported by a bearing assembly 47. The bearing assembly 47 is supported in a channel 48 (Fig. 5) provided by the plate 22 of the base. The bearing assembly is attached to the base by bolts 49 which are shown in Fig. 2. The outer end of the pinion shaft 46 is provided with a drive sprocket 51 over which a chain (not shown) is extended for driving the shaft.

Formed integrally with the plate 22 at op-

posite sides thereof and extending longitudinally thereof are pairs of outer and inner longitudinal ribs 55 and 56. The pairs of ribs 55 and 56 extend downward from the plate 22. This is clearly shown in Figs. 4 and 5. The ends of the pairs of ribs 55 and 56 are rounded as illustrated in the drawings, and are closed by curved end plates 57 which form a part of the base 21 and are integral with the other parts thereof. The pairs of ribs 55 and 56 are attached together and rigidified by webs 58. This is clearly shown by dotted lines in Fig. 3. It should be noted that the webs 58 are placed at intervals along the pairs of ribs. As shown best in Figs. 2, 4 and 5, sole plates 61 are placed against the lower ends 62 of the pairs of ribs 55 and 56 and are welded thereto as indicated at 63. The sole plates 61 not only provide bearing faces for the pairs of ribs 55 and 56 but reinforce them greatly, making the base very strong.

As shown best in Figs. 3 and 5, cross webs 65 and end webs 66 are extended transversely across the plate 22 between the ribs 56. These cross webs 65 and end webs 66 are formed integrally and extend downward from the plate 22. They are not extended down, however, as far as are the ribs 55 and 56.

It should be noted that the base 21 is an integral structure with the exception of the sole plates 61. The sole plates 61 are attached to the base, however, by autogenous welding and therefore may be considered as integral. The purpose of the longitudinal ribs 55 and 56 and the sole plates 61 is two-fold; first, they serve as skids whereby the rotary machine is supported; and second, a very important function of these constructions is to make the base 21 rigid. The ribs 55 and 56 extend the entire length of the base 21 and quite fully reinforce the plate 22. The ribs 55 and 56 are in themselves reinforced by the cross webs 58 and also by the sole plates 61. It will be seen that this results in a strong structure. The plate 22 is further reinforced by the cross webs 65 and the end webs 66.

The rotary table of this invention is an innovation in the art of drilling wells by the rotary system. As pointed out above the bases of the rotary table have been made in two parts and the skids have been made of wood and have been made a separate part. A much superior base is provided by my invention. The special construction of the base provides one which is much stronger than that of the ordinary rotary table and is capable of enduring all strains to which a rotary machine is subjected during the usual deep well drilling operations. The weight of the base is not any more than that of the rotary machine and is not objectionable for that reason. In the ordinary construction of base it was necessary to make it quite thick

so that there would be no bending. This resulted in that the top of the table was too high for purpose of convenient handling of the pipe slips. In my invention the top of the rotary table is much lower and permits the pipe slips to be conveniently handled.

I claim as my invention:

1. In a rotary machine, the combination of: an integral base structure having a horizontal plate, and pairs of depending longitudinal ribs extended along opposite sides of said plate, said longitudinal ribs reinforcing said plate and serving as skids; sole plates attached to the lower ends of said longitudinal ribs, said sole plates reinforcing said longitudinal ribs and providing bearing faces therefor; a rotary table journaled on said base; and mechanism supported by said base for driving said rotary table. 75

2. In a rotary machine, the combination of: an integral base structure having a horizontal plate, pairs of depending longitudinal ribs extended along opposite sides of said plate, said longitudinal ribs reinforcing said plate and serving as skids, webs for reinforcing said pairs of longitudinal ribs, and transverse webs for reinforcing said plate; sole plates attached to the lower ends of said longitudinal ribs, said sole plates reinforcing said longitudinal ribs and providing bearing faces therefor; a rotary table journaled on said base; and mechanism supported by said base for driving said rotary table. 80

3. In a rotary machine the combination of: an integral base structure having a horizontal plate, and pairs of longitudinal ribs depending from opposite sides of said plate, said pairs of longitudinal ribs reinforcing said plate and serving as skids therefor; sole plate means secured to the lower edges of said longitudinal ribs and providing bearing faces therefor; a rotary table journaled on said base; and mechanism supported by said base for driving said rotary table. 95

In testimony whereof, I have hereunto set my hand at Los Angeles, California, this 1st day of November, 1926.

EDWIN W. GOESER.
